UNITED STATES PATENT OFFICE.

CHARLES W. SMITH, OF CINCINNATI, OHIO.

SIGN.

Application filed August 20, 1923. Serial No. 658,358.

My invention relates to displaying devices, and more especially to devices of this character adapted to be illuminated by day light or by artificial light, for day and night display.

The object of my invention is to provide for maximum efficiency of illumination by artificial light by advantageous disposition of the display surfaces of the sign relatively to the lighting means, as well as to provide a compact and simple construction of the sign, economical to manufacture and having a pleasing appearance both in daylight and when artificially illuminated, with a minimum of detail so that the attention is not diverted from the matter displayed on the sign. Other objects will appear in the course of the ensuing description.

I attain these objects by the device illustrated, for example, in the accompanying drawing, in which—

Figure 1 is a front elevation of a double faced sign embodying my invention;

Fig. 2 is a horizontal cross-section on the plane of the line 2—2 of Fig. 1;

Fig. 3 is a vertical cross-section on the plane of the line 3—3 of Fig. 1; and

Fig. 4 is a front elevation of a modified sign embodying my invention.

In the example of Figs. 1, 2 and 3 the sign is of rectangular general formation. It comprises the outer frame-like structure or member 1, preferably made of sheet metal in hollow triangular cross-section with an outer shell 2 forming the top, bottom and opposite upright ends of the structure; which shell 2 has the flanges 3 turned up along its opposite longitudinal edges. The other two sides 4 and 5 of the triangular cross-section of the upper part of this frame member 1 have their upper edges 6 flanged over the flanges 3, and meet to form the edge of the aperture 7 of the frame, where the side 4 has the flange 8 turned up under the edge of the other side 5. Likewise, the lower part of the frame is made up of the sides 4' and 5' with their lower edges 6' turned up under the lower flanges 3 of the shell 2 and their upper edges meeting with the flange 8' of the side 4' turned down over the edge of the side 5', forming the lower edge of the aperture 7; and the upright parts are made up each of sides 4'' and 5'' with outer edges 6'' turned over the lateral flanges 3 of the shell 2 and their inner edges meeting to form

the lateral edges of the aperture 7, with the edge 8'' of the side 4'' turned around the edge of the other member 5''. The ends of these sides 4 and 5, 4' and 5', and 4'' and 5'' are beveled to fit closely together, and the joints between these ends are suitably secured, as by soldering, preferably with the meeting ends lapping, although in the drawing, for simplicity of illustration, these joints 9 are shown merely by single lines. Also an important detail is that the sides 4, 5, 4', 5', 4'' and 5'' are concave on their outer or display surfaces. This affords a better distribution of light across the entire width of each side.

Riveted to the outer sides of the shell 2, at opposite ends of the upper part of the member 1 are hooks 10 extending above the top of the member 1 to hook over a suitable support, as the rod 11 which may be fixed to the building or other object upon which the sign is displayed. Any other desirable method of supporting the member 1 may be substituted.

Near the respective corners of the aperture 7 the hooks 12 are secured to the sides of the member 1 across their joints 9, by conical sheet metal bases 13 soldered to the shanks of the respective hooks and to the sides of the member; all of these hooks being directed upward.

The casing 14 is an elongated box-like structure of sheet metal, not as high as the aperture 7 of the member 1, and mounted transversely along this aperture with about equal spaces 15 and 15' above and below within the aperture. The ends 16 of this casing 14 are tapered and are recessed to straddle the upright edges of the aperture where the upright sides 4'' and 5'' are joined by the flange 8''; these ends 16 being soldered to these sides 4'' and 5''. At the left end, however, the sides 4'' and 5'' are spread apart about midway of their height, interrupting their seam and cutting through the flanged part 8'', to form a cylindrical entrance 17 in which is fitted an insulating bushing 18. In horizontal alignment with this bushing, the outer shell 2 has an opening with a bushing 19; and the cable 20 leads in through the aligned bushings 18 and 19, into the interior of the casing 14. The two opposite upright sides of the casing 14 have apertures suitably distributed, and lamp sockets 21 are mounted in these

apertures, opening outward at the respective sides to receive the electric lamps 22. The cable 20 is made up of two conductors 23 and 24, from which short leads connect 5 with the several lamp sockets 21, to supply current to the lamps 22 in the usual manner. As shown in the drawing, there are four lamps 22 in an upper row and four in a lower row, along each side of the casing 14.

The translucent members 25 extend before the aperture 7 at the opposite sides of the sign; each, as here shown, being made up of a glass plate 26, which it will be understood may be an opal glass, or other translucent glass; or any suitable other translucent material may be substituted, or combinations of them with transparent bodies. This plate 26 has a frame 27 entirely around it, preferably of wood, although a metal frame may be used; the plate 26 and its frame 27 being rectangular, of about the same proportions as the aperture 7 of the member 1. Near the respective corners of the frame 27, eyes 28 are screwed or otherwise suitably secured thereto; each eye as shown being made of a flat strip of metal with members at right angles to each other; the longer member being secured to the frame 27 and the shorter member having an opening by which the eye is constituted. These eyes 28 are located on the frame so that each eye can slip onto a respective one of the upturned hooks 12 of the member 1, whereby the member 25 is detachably hung on the member 1; the hooks 12 projecting far enough for the inner surfaces of the members 25 to clear the outer ends of the lamps 22 at the respective sides of the sign.

In the modification of Fig. 4 the member 1^a is of circular shape, with the outer shell 2^a and the sides 4^a and 5^a joining it by suitable means, as flanges similar to the flanges 3 and 6 of the first example, and having their inner edges together and joined in a suitable manner, as by a flange 8 as in the first example; it being understood that this circular sign would have substantially the appearance, in cross-section, of that of the first example as shown in Fig. 3. In this circular sign, the sides 4^a and 5^a are conveniently made of disks, apertured in their centers and formed to the required shallow dished shape to make the triangular cross-section along with the outer shell 2^a; the central aperture 7^a of this circular member 1^a being circular. Three of the hooks 12 are provided, spaced equally around the aperture 7^a, two above and one below; and these will be understood as being suitably strongly connected to the member 1^a, as by the conical bases 13 of the previous example.

The casing 14^a is of drum shape, smaller 65 than the aperture 7^a, leaving an annular

space interrupted by small extensions 16^a at opposite sides, attached to the drum or casing and fixed to the edges of the aperture 7^a, similarly to the ends 16 of the casing 14 of the first example; so that there are open spaces 15^a and 15^b above and below this casing, in the aperture 7^a. The sides 4^a and 5^a have their seam around the aperture interrupted at one side, within one of the extensions 16^a, receiving a bushing 18 in the entrance 17 thus formed; and the shell 2^a has the opening with the bushing 19 alined therewith, admitting the cable 20 to supply current to the lamps 22 arranged in a circle around the face of the casing 14^a; the interior connections of which will be understood to be as those of the casing 14 in the previous example. The member 1^a has hooks 10^a fitting over the supporting rod 11, as previously described for the other example.

The translucent member 25^a also is circular, comprising the circular plate 26^a and annular frame 27^a, with three eyes 28 to fit on the hooks 12 of the member 1^a.

Display matter 29 on the display surfaces of the sides 4 and 5 of the member 1, or sides 4^a and 5^a of the member 1^a, is illuminated directly by the lighting means constituted by the lamps 22 and casing 14, or lamps 22 and casing 14^a, since these surfaces incline out through the vertical plane of the lamps; and also by light of these lamps reflected from the inner surface of the translucent member 25 or 25^a at the respective side of the sign. Also, to some extent, light is reflected from the inner surface of a translucent member 25 or 25^a at one side to and through the opposite translucent member; part of this light being reflected from this opposite member to the display surface of the member 1 or 1^a at that side. Thus, display matter 30 on the outer or inner surface of the translucent member 25 or 25^a is illuminated by passage of light through or around the matter; and this appears along with the matter 29 on the display surface of the outer member 1 or 1^a substantially as if the entire matters 29 and 30 were on one continuous surface. A much better distribution of light is effected, however, than if there were a single continuous translucent member; as a few lamps near the center of the sign would not light the outer regions thereof unless bright enough to excessively light the central region; and a single continuous opaque surface, corresponding to surface of the member 1 or 1^a, would require the lamps at one or more edges, as is the practice with large signs, failing to illuminate the central region without excessively illuminating the outer regions. Moreover, the large number and powerfulness of the lamps thus required is expensive; and my invention permits con-

siderable economy in light, while at the same time affording a much more uniformly illuminated display.

By having the translucent member 25 or 25^a detachable from the other member 1 or 1^a, each member may have its display matter placed thereon, as by painting or otherwise, while the members are separated; permitting much easier access to the display surface at either side of the member 1 or 1^a. Also, removal of the member 25 or 25^a affords full access to the lamps 22, when these are to be renewed.

In each example, a sign for displaying on both sides has been set forth; such signs being useful to hang extended from buildings, to be seen at approach in either direction along the street, and the mode of mounting the sign, by the rod 11, being especially adapted for this. However, it will be seen that a sign for display at only one side thereof may be employed according to my invention; having the advantages just pointed out, in that light from the lamps 22 at the one side will shine out across the inclined surfaces of the member 1 or 1^a as well as through the member 25 or 25^a, with part of the light reflected from the inner side of the latter member to the surface of the former member. Also, such a sign, with the translucent member detachable, will have the advantages just before noted, due to this arrangement. Such a sign, displaying at one side only, may be placed along the wall of a building or the like; and either the single side or double side display may be embodied in very small doorway signs, or very large bulletins, such as occupy roadside or the tops of large buildings. A rectangular sign and a circular sign have been exemplified; but other shapes may occur, with details arranged accordingly. The translucent members may have any degree of transparency.

Other modifications are probable, and therefore, although various details of my invention have been described somewhat specifically, to make clear the construction and use thereof, as is required, I do not wish

to be understood as being limited to such precise showing and description, but—

What I claim as new and desire to secure by Letters Patent is:

1. A sign comprising spaced apart translucent members having display surfaces, a casing between said members, an additional member having diverging sides with display surfaces diverging from near said casing out beyond edges of the respective translucent members, lighting means supported on said casing opposite the respective display surfaces of the translucent members, said casing being attached to the approached edges of said diverging sides of the additional member, and a connection leading between said diverging sides and out therefrom at said approached edges, into said casing, to said lighting means.

2. A sign comprising spaced apart translucent members having display surfaces, a casing between said translucent members, an additional member having display surfaces diverging from near said casings in various directions out beyond various edges of the respective translucent members, lighting means supported on said casing opposite the respective display surfaces of the translucent members, said casing having opposite ends attached to approached edges of said diverging sides of the additional member, and a connection leading between said diverging sides and out therefrom into one end of said casing, and leading from said end to said lighting means.

3. A sign comprising a structure with an inner aperture and a surface inclined to said aperture and bearing a display, lighting means in said aperture, and a translucent member opposite said aperture in such relation to said lighting means and said inclined surface as to reflect part of the light from said lighting means to said inclined surface, said translucent member bearing a display the effect of which is increased by the other part of said light transmitted by said translucent member.

CHARLES W. SMITH.
